ROCKING DEVICE

May MacGregor, New York, N. Y., assignor to
 Richard Hudnut, New York, N. Y., a corpora-
 tion of New York

Application January 17, 1948, Serial No. 2,827

1. Claim. (Cl. 128—33)

1

This invention relates to a method and apparatus for the administration of beauty treatments. In particular it pertains to the treatment of individuals while completely relaxed and disposed in a supine position in a manner intended to stimulate and increase the circulation of blood throughout the body and to thereby induce increased tissue nourishment in the face of the subject taking the treatment.

The tendency toward tissue anemia is recognized to be considerably greater in the upper body extremity and this condition is apparently due to the fact that circulation in that direction is substantially influenced by the action of gravity. This tendency for example is evident to an extent in the facial contours of the aged as contradistinguished from the more normal condition present in the lower portions of the anatomy. The effect of gravity on circulation is especially noticeable when the feet are raised above the head. It is also known that any form of activity which increases the circulation has a beneficial effect on the cardio-vascular system which in turn reacts to improve the condition of the surrounding tissues. Also medical opinion has held the maintenance of a healthy circulatory condition tends to offset premature deterioration of tissue.

It is an object of the present invention to provide a device and method of stimulating the circulation requiring no effort on the part of individuals.

Another object of the invention is to provide a method for increasing the flow of blood to the head and face.

Another object of the invention is to relieve body fatigue by equalizing and controlling the circulation of blood in the body.

Another object of the invention is to provide an improved form and method of giving beauty treatments and a device to be used in practising the same.

An additional object is to provide a device and method for controlling the circulation in harmony with normal bodily functions.

In accordance with the present invention it has been discovered that the circulation may be artificially induced and increased with resulting beneficial effects when the individual is subjected to a rocking motion while disposed in a supine position on a device designed to rock or oscillate lengthwise with respect to the individual in timed relationship with the heartbeat.

In practicing the invention, the pulse or heartbeat is first timed by a recording device such as a metronome which is synchronized with the

heartbeat. The individual then reclines on the rocking device which is oscillated automatically or by an operator in a movement which is harmonized with the metronome or other device, so that the circulation is stimulated in relation to the heartbeat.

The device used in carrying out the method of treatment in accordance with the invention preferably comprises an elongated support or bed for accommodating the individual in supine position with one or more substantially semi-circular rocking members lengthwise of the support for allowing an appreciable inclination of the device during the treatment. The device may be and preferably is provided at either end with means for preventing endwise movement of the patient relative to the support during the treatment. The aforesaid means are preferably adjustable to accommodate individuals of various sizes and shapes and firmly position them on the support during the treatment. Suitable means such as blocks or stabilizers pivoted to the rockers may be provided to maintain the elongated supporting surface in a horizontal position before starting the treatment.

A particular form of device for carrying out the method of treatment is shown in the accompanying drawings for purposes of illustration. It is to be understood that the device shown and described is but a single embodiment and changes may be made without departing from the scope of the claim.

In the drawings:

Figure 1 is an elevation of the rocking device in horizontal position.

Figure 2 shows a plan view thereof.

Figure 3 is an end view.

Figure 4 is a detail showing the shoulder cushions inoperative.

Figure 5 is a section on the line 5—5 of Figure 4.

Figure 6 is a detail of the foot rest.

Figure 7 is an elevation of the device in operation.

Figure 8 is a section on the line 8—8 of Figure 7.

Figure 9 is a detail of a shoulder cushion.

Referring to the drawings the device is shown as comprising a rectangular mattress 10 supported upon a rocking apparatus designated in general by the numeral 11. This rocking device 11 is preferably constructed of light-weight metal such as aluminum or magnesium alloy tubing so as to be easily manipulated by an operator and comprises a pair of semicircular rocker members 12 welded or otherwise secured at their extrem-

ties to the ends of side members 14 and end members 15 which are in turn secured together to provide a support for the mattress or bed 10. The latter rests in part upon an endless webbing or band 16 stretched between the side members 14 as shown in Figure 5.

The rockers 12 are provided with braces 17 to support said rockers laterally and with segmental supports 18 to preclude circular distortion of the rockers during the treatment. In order to provide means for stabilizing the device 11 at a position of rest with the mattress 10 in a horizontal position, a pair of stabilizing blocks or feet 19 are pivotally mounted between the rockers 12 substantially equidistant from the centerpoints thereof. The stabilizing blocks 19 remain in the supporting position shown in Figure 1 until the device is placed in operation whereupon they may be elevated clear of the rocking surfaces and maintained in retracted position by clasps 20 mounted on the segmental supports 18. To firmly position the patient relative to the mattress 10 during the treatment, an elongated tubular element 21 is mounted above each of the side members 14 at the sides of the mattress 10 by a number of brackets 22. Slidably contained within the lower ends of the tubes 21 are rods 23 forming part of a footrest 24. The footrest 24 is adjustably positioned relative to the lower end of the mattress 10 by set screws 25.

The opposite or head ends of the tubes 21 each slidably receive the free end of a broken rod 26 which terminates at the opposite end in a bracket support 27 for the shoulder rest 28. The bracket support 27 is journaled to slidably receive a hexagonal shaft 29 which forms a support for the shoulder rest 28. A set screw 30 serves to adjustably position the hexagonal shaft 29 relative to bracket support 27.

The broken rod 26 is formed of a short section or end 31 pivoted to a relatively long section 32. It is apparent the entire rod 26 may be moved into the tube 21 and positioned therein at any desired adjustment by a set screw 33.

The obvious purpose and function of the above arrangement is to permit a maximum range for adjusting the shoulder rests 28 to various individuals before the end 31 of rod 26 reaches the end of tube 21 and at the same time to allow the shoulder rests to repose at the sides of the device when inoperative. Moreover, the arrangement permits adjustment of the shoulder rests both longitudinally and laterally which in combination with the adjustable footrests renders the device readily capable of firmly positioning individuals of various sizes and shapes relative to the mattress or bed.

It is desirable, that the heartbeat be recorded sometime before beginning the treatment when the patient is completely relaxed to insure recordation of the normal heartbeat. The method of the present invention may be carried out with the patient positioned on the rocking device by

the adjustable means aforesaid and after the blocks 19 have been moved to inoperative position.

The device is then oscillated or rocked by an operator in a cadence which is timed with the metronome or other device previously employed for timing the pulse and which during the treatment either audibly or otherwise repeats the cadence of the pulse. It is generally advisable that the device be rocked at a small angle at the start and the degree of inclination in either direction gradually increased. This serves to gradually condition the circulatory system to the rhythm of the treatment without causing discomfort or untoward reaction in the patient. For example, the treatment may begin with the device being gradually rocked at an angle of about 20 degrees from the horizontal in either direction while counting 4 beats from the recording device from top to bottom of a single movement. This may be continued for about 10 minutes and the angle of rock increased to 30 degrees with the same count. The treatment is ordinarily continued for about 10 minutes for best results.

The beneficial effects of the present treatment are immediately evident to the patient who feels at once relaxed and refreshed upon completion of the treatment. If desired the treatment may be repeated at frequent intervals without ill effect or untoward reaction.

I claim:

A device for the administration of treatments to a patient, comprising a support for accommodating the patient in a supine position, said support being mounted upon a structure including a pair of longitudinally extending, substantially semi-circular rockers, stabilizing means pivotally attached to said structure between the center and one of the ends of each of said rockers at points equidistant from the center of said rockers, each of said stabilizing means being constructed of two arms, the extremities of which are adapted to engage the surface upon which the rockers rest, joined at an apex at which said means are pivoted, and a clamp on said structure for each of said stabilizing means to hold said stabilizing means in retracted position while the device is being rocked.

MAY MACGREGOR.
